UNITED STATES PATENT OFFICE

119,199

DESIGN FOR A LAPEL PIN

Brian Smith, Dallas, Tex.

Application May 29, 1939, Serial No. 85,250

Term of patent 3½ years

To all whom it may concern:

Be it known that I, Brian Smith, a citizen of the United States, residing at Dallas, in the county of Dallas and State of Texas, have invented a new, original, and ornamental Design for Lapel Pins, of which the following is a specification, reference being had to the accompanying drawing forming part thereof.

I claim:

The ornamental design for a lapel pin, as shown.

BRIAN SMITH.
